This technical drawing illustrates a mechanical assembly, likely a component of a larger machine. The drawing is labeled with various numbers (1 through 25) and includes a callout labeled 'FIG. 2'.

- FIG. 2:** A callout showing a cross-sectional view of a cylindrical component. The cross-section is labeled with the number 16. The outer wall of this component is labeled with the number 18. A vertical dimension line indicates a height of 18 for the entire component.
- FIG. 1:** A callout showing a side view of a rectangular component. The top surface is labeled with the number 5. The side wall is labeled with the number 6. A vertical dimension line indicates a height of 5 for the component.

The main assembly features a base structure with legs and a central frame. Key components include:

- A horizontal beam (part 2) supported by legs (part 1).
- A central frame (part 3) with a slot (part 24) for a rod (part 21).
- A rod (part 21) with a U-shaped bracket (part 20) and a spring (part 25).
- A vertical support (part 8) with a slot (part 9) for a rod (part 10).
- A rod (part 10) with a U-shaped bracket (part 17) and a spring (part 23).
- A central vertical post (part 16) with a slot (part 18) for a rod (part 10).
- Base legs (part 4) with feet (parts 5, 6, 7, 8, 9, 10, 11, 12, 13, 14, 15).

UNITED STATES PATENT OFFICE

2,433,899

VISE FOR CLAMPING THE END PORTIONS
OF CABLES OR ROPES

Floyd R. Granger, San Pedro, Calif.

Application June 15, 1945, Serial No. 599,653

2 Claims. (Cl. 81—17.4)

1

The present invention relates to a vise for clamping the end portions of a cable or rope in such a manner that a wire rope socket may be slipped over such portion.

The main object of the invention is the design of an apparatus serving the above purpose and suitable for different sizes of cables or ropes.

Another object of the invention is the design of a clamping device of simple, sturdy and inexpensive construction which can be operated by a person without special training and experience.

With these objects and others as will become apparent from the following disclosure, the invention resides in the novelty of features, combination and arrangement of parts as described in the following description and illustrated in the accompanying drawing forming part of this application and in which:

Figure 1 is a top plan view of the preferred embodiment of my invention in inoperative or open position;

Figure 2 is an enlarged top plan view in operative or clamping position;

Figure 3 is a still more enlarged longitudinal, central and vertical section on line 3—3 of Figure 2;

Figure 4 is an enlarged transverse, vertical section on line 4—4 of Figure 1;

Figure 5 is an enlarged transverse, vertical section on line 5—5 of Figure 2.

In the drawing in which like reference characters designate like or similar parts, numeral 2 denotes one of four legs which are of angular cross section and converge upwardly. At an intermediate point these legs are connected by a brace 3 which takes the form of a plate and may also serve as a shelf for tools, supplies and the coiled portion of a wire rope the end portion of which is to be clamped in the device being described.

The plate may be connected to the legs by any suitable means preferably welding. Another plate 4 is supported by the upper ends of the legs and connected thereto by welding or otherwise. Upon opposite marginal end portions of the top side of this plate strips 5 are secured by bolts 6. Angle irons 7 having their horizontal flanges extending toward one another are mounted upon plate 4 between said strips to function as guides for a structure to be described. The angle irons extend considerably beyond one side of plate 4 and are provided throughout their lengths with guide strips 8 of a width of about one-third of the width of the horizontal

2

flanges to which they are secured. The narrow vertical edges of these strips are in contact with the lower portion of the inner side of the vertical flanges and their bottom faces rest on the inner portion of the horizontal flanges. A pair of narrow guide flanges 9 are each vertically spaced from and above the guide strips and fixed to the upper inner marginal portion of the vertical main flange and extend throughout that portion of the angle irons which overhangs the table described and for a short distance over that portion of the angle irons resting on the table.

A slide 10 (Figures 1—4) of suitable material, preferably iron, is shaped for cooperation with the guide structure described and consists of a top portion slidable between the guide flanges 9 and a bottom portion having lugs 11 that slide between the guide strips 8 and flanges 9. To the outer or righthand (Figures 1—3) side of this slide are affixed by welding or otherwise two parallel spaced horizontally disposed plates 12, 13; the upper plate 12 slides beneath the guide flanges 9 while the bottom plate 13 slides upon the horizontal flanges of angle irons 7 and between the guide strips 8. These plates have on their free front edge angular cut-outs 14 of about 60° for a purpose which will become clear as the description proceeds.

Between the movable plates described is disposed a stationary plate 15 which has a similar cut-out 16 facing in a direction opposite that of the cut-outs in the first described plates. The rear end of plate 15 has a flange 17 whereby it is welded to a rod 18 mounted in the vertical flanges of the angle irons. Figure 5 shows the outlines of the flange 17 partly in dotted lines.

To effect the motion of the slide the following mechanism is provided. The slide has in the center of its upper portion an aperture which is lined by a bearing ring 19 in which the reduced portion of a screw 20 is journaled. On the rear side of the slide a nut 21 is threaded on the reduced portion which carries on the front side of the slide a washer 22 and nut 23. On the left-hand end of the table and angle irons is an abutment 24 which has a U-shaped (Figures 1, 2) boss 25 on its inner side. The boss and abutment have a threaded hole for the screw which carries upon its outer end a hand wheel 26 with a handle 27 extending outwardly and at right angles to the plane of the wheel.

In order to operate the device described the hand wheel is turned in the proper direction to retract the slide and the plates carried thereby until the cut-outs in the three plates have a cross

sectional area large enough for the passage of the cable or rope C, the end of which is to be fitted with a wire rope socket. The hand wheel is then turned in the opposite direction until the rope end is clamped in the cut-outs and between the plates. Since the strands of the rope or cable are loosely pressed together, the wire rope socket may be slipped with ease over the rope end protruding above the plates.

The foregoing description describes and the accompanying drawing illustrates a preferred embodiment of my invention. However, it is to be understood that the specific details of this embodiment are not limitations, but mere examples of my invention, and that in adapting the same to meet different conditions, various changes in form, proportion, and minor details of construction may be resorted to without departing from the spirit and scope of the invention as defined in the appended claims.

What I claim and desire to secure by Letters Patent is:

1. In a vise, an elongated supporting frame having a plate member disposed therein and fixed thereto and provided with a notch at one end thereof, forming a fixed vise jaw, a movable vise jaw slidably disposed in the supporting frame, guide means for slidably supporting the movable vise jaw in the frame and relatively to the fixed vise jaw, said movable vise jaw including a plurality of spaced plates forming a space therebetween in which the fixed jaw is receivable and between which said fixed jaw is closely engaged, said plates of the movable jaw having notches in an end thereof, opposite to the notched end of the fixed jaw and combining therewith to form a substantially diamond shaped opening as the movable jaw is moved toward a projected position and into telescopic engagement with the fixed jaw and manually actuated means for moving the movable jaw toward and away from said fixed jaw, said supporting frame including side rails between which the movable jaw is slidably disposed and which are provided with inwardly extending horizontal portions provided with upstanding guide strips for slidably supporting the bottom plate of the movable jaw and on the upper side of which the fixed jaw is supported, and said side rails having upstanding longitudinal flanges provided with inwardly extending guide strips, between which and the upper side of said fixed jaw, the upper plate of the movable jaw is slidably supported.

2. In a vise, an elongated supporting frame having a plate member disposed therein and fixed thereto and provided with a notch at one end thereof, forming a fixed vise jaw, a movable vise jaw slidably disposed in the supporting frame, guide means for slidably supporting the movable vise jaw in the frame and relatively to the fixed vise jaw, said movable vise jaw including a plurality of spaced plates forming a space therebetween in which the fixed jaw is receivable and between which said fixed jaw is closely engaged, said plates of the movable jaw having notches in an end thereof, opposite to the notched end of the fixed jaw and combining therewith to form a substantially diamond shaped opening as the movable jaw is moved toward a projected position and into telescopic engagement with the fixed jaw and manually actuated means for moving the movable jaw toward and away from said fixed jaw, said supporting frame including side rails between which the movable jaw is slidably disposed and which are provided with inwardly extending horizontal portions provided with upstanding guide strips for slidably supporting the bottom plate of the movable jaw and on the upper side of which the fixed jaw is supported, and said side rails having upstanding longitudinal flanges provided with inwardly extending guide strips, between which and the upper side of said fixed jaw, the upper plate of the movable jaw is slidably supported, and said movable jaw having an end wall, remote to the fixed jaw and provided with extensions at the ends thereof slidably disposed between said guide strips.

FLOYD R. GRANGER.
